UNITED STATES PATENT OFFICE.

ROY G. MAKINSON, OF BUTTE, MONTANA.

SMOKE-CONSUMING DEVICE.

Application filed July 29, 1922. Serial No. 578,375.

To all whom it may concern:

Be it known that I, ROY G. MAKINSON, a citizen of the United States, residing at Butte, in the county of Silver Bow and State of Montana, have invented certain new and useful Improvements in Smoke-Consuming Devices, of which the following is a specification.

The invention relates to smoke consuming devices for stoves or furnaces, and has as an object the provision of such a device that shall consume the smoke and combustible gases effectively, and shall utilize the heat derived from such combustion.

15 A further object of the invention is the provision of a smoke consuming device wherein the gases from the fire are conducted through an annular flue surrounding the fire pot with admission of flame and air to the flue for combustion of the gases. A further object of the invention is the provision of a smoke consuming device having means for admission of water vapor and air to aid in the combustion. Further objects 20 will appear from the following description when read in connection with the accompanying drawings showing an illustrative embodiment of the invention, and wherein

Fig. 1 is a detail perspective view of the 30 device partly broken away;

Fig. 2 is a detail side elevation of a bypass;

Fig. 3 is a detail side elevation showing an end view in connection therewith of an 35 air admission adjustment device;

Fig. 4 is a detail vertical section on line 4-4 of Fig. 1, and

Fig. 5 is a horizontal section on line 5-5 of Fig. 4 looking in the direction of the 40 arrow.

As shown the device is in the form of an annular fire pot or flue 10 wherein the grate is located at 11, the fire pot being formed of some refractory material, such as cast iron, or fire brick.

45 A smoke pipe 12 is shown communicating with the interior of the annular fire pot or flue, a partition being provided at 13 which completely divides the space within the flue.

50 A collar 14 is shown making a tight joint at its lower edge 15 with the upper surface of the fire pot 10 and opening into the same at 16 beyond the partition 13, which partition extends across the fire pot in a vertical 55 plane forming a downward extension of one

side of the smoke pipe 12. The smoke and gases from the interior of the fire pot are drawn by the draft of the furnace in a course shown by the lines 17 over the edge of the collar, and through the space 16 into 60 the interior of the annular flue, after which the gases encircle the flue, as indicated by the dashed lines until they reach the proximity of the partition 13, when they are drawn up smoke pipe 12.

65 The gases being in a highly heated condition as they leave the fire and the inner wall of the flue 10 being in contact with the burning fuel maintains the heated condition of the gases in their course through 70 the annular flue. To ensure the combustion of the gases while passing through the flue, small openings 18-19 are shown through the interior wall of the flue through which openings flame may be drawn from the fire 75 for the purpose mentioned.

To provide air for combustion of the gases in the flue, pipes 20-21 are shown which extend to the exterior of the stove or furnace. For control of the admission 80 of air through the pipes 20-21 a device, such as shown in Fig. 3, may be applied to such pipes, comprising a threaded extremity 22 of the pipe and an interiorly threaded sleeve 23 coacting therewith. A portion of 85 the wall of the pipe may be cut away as at 24 so that the screwing inwardly of the pipe 23 will more or less close the opening produced by the cutting away of the pipe. In addition to this control a damper 25 may be 90 provided in the end of the pipe.

To check the flow of the gases in their course about the flue and to provide an additional suction upon the air pipe 21, a baffle 26 is shown extending across the annular space and throughout a portion only 95 of its depth. The admission opening 19 for flame is shown just behind this baffle, and the connection of pipe 21 with the flue is in the rear of the baffle, so that the slight excess of vacuum caused by the baffle will result in a drawing in of air through the pipe 21 and flame, through the opening 19 in excess of the amount which would be drawn without the baffle.

100 When starting a fire with the fire pot cold the draft might have difficulty in drawing the smoke through the tortuous channel provided by the annular flue, and moreover the walls of the flue would not be heated hot 110

enough to cause combustion of these gases. Also, when the furnace door is opened, an easier escape being provided for gases, might cause escape of gas into the room in which the furnace is located. To avoid these difficulties, a by-pass is shown in the form of a damper 27, shown in detail in Fig. 2. As shown, the damper is pivoted at 28, and is provided with a weight 29 integral with the lower edge thereof to ensure the tight closing of the damper. The damper may be opened when desired by means of a rod 30 acting upon a lever 31, the rod 30 passing to the exterior of the stove or furnace. A notch is shown at 32 which may coact with the wall of the furnace 33 to hold the damper open when desired.

To provide a supply of steam to the air for combustion, in the annular chamber, a receptacle 34, located within the furnace, is shown, and a pipe 35 extends from the top of the receptacle to the interior of the pipe 20, dipping downwardly therein so as to have its mouth adjacent to the mouth of the pipe 20 within the flue.

Water may be supplied to the receptacle 34 by means of a pipe 36 in communication with a reservoir 37 exterior of the furnace but of less height than the receptacle 34, so that the supply of water shall not overflow into the pipe 35. A check valve is shown at 38 so that steam pressure within the receptacle 34 can not drive the water back into the reservoir 37. A pipe 39 is shown which may be connected to the water supply of the building.

While the flue of the fire pot is shown as circular in its horizontal cross section, it will be understood that the same will be made to fit the fire pot of the stove or furnace no matter what its form, whether circular, rectangular or polygonal, it being only necessary that the same should surround the combustion space and be in contact with the fire upon its interior walls to accomplish the purpose described.

Minor changes may be made in the physical embodiment of the invention without departing from its spirit.

50 What I claim is:

1. In a smoke consuming device, in combination, an annular flue comprising a closed space having inner and outer walls, said flue adapted to have its inner walls in contact with the fire, a smoke pipe in direct communication with said flue, said flue having an opening adjacent the smoke pipe for admission of products of combustion, and means within the flue to cause the products of combustion to encircle the flue to reach the smoke pipe.

2. In a smoke consuming device, in combination, an annular flue comprising a closed space having inner and outer walls, said flue adapted to have its inner walls in con-

tact with the fire, a smoke pipe in direct communication with said flue, said flue having an opening adjacent the smoke pipe for admission of products of combustion, means within the flue to cause the products of combustion to encircle the flue to reach the smoke pipe, and means to admit air to said flue to complete combustion of unburned gases.

3. In a smoke consuming device, in combination, an annular flue comprising a closed space having inner and outer walls, said flue adapted to have its inner wall in contact with the fire, a smoke pipe in direct communication with said flue, said flue having an opening adjacent the smoke pipe for admission of products of combustion, means within the flue to cause the products of combustion to encircle the flue to reach the smoke pipe, means to admit air to said flue to complete combustion of unburned gases, and means to admit flame to said flue to ignite said unburned gases.

4. A smoke consuming device comprising, in combination an annular fire pot having inner and outer walls providing an annular flue therebetween, upper and lower walls closing the flue space between said inner and outer walls, a smoke pipe in communication with said flue, a partition in said flue adjacent one side of said pipe, an opening in said upper wall adjacent said partition for admission of products of combustion to said flue, said partition being between said opening and the communication with said smoke pipe.

5. A smoke consuming device comprising, in combination, an annular flue providing a combustion space therewithin, an opening into said flue for admission of products of combustion from above the fire, a smoke pipe communicating with said flue adjacent the opening, a partition dividing said flue between the opening and smoke pipe whereby gases entering said flue must encircle the same to reach the pipe, a baffle in said flue to check said gases and means to admit air behind said baffle.

6. A smoke consuming device comprising, in combination, an annular flue providing a combustion space therewithin, an opening into said flue for admission of products of combustion from above the fire, a smoke pipe communicating with said flue adjacent the opening, a partition dividing said flue between the opening and smoke pipe whereby gases entering said flue must encircle the same to reach the pipe, a collar about said opening, said collar enclosing and spaced from the base of said smoke pipe, a baffle in said flue to check said gases and means to admit air behind said baffle.

7. A smoke consuming device comprising, in combination, a flue adapted to be in contact with the fire at one wall thereof and

having an opening for admission of gases from above the fire, means for admitting air to the flue comprising an inlet pipe having a threaded extremity and a cutaway portion adjacent thereto, a sleeve adapted to be screwed upon said extremity to cover more or less of said cutaway portion and means to close the free end of the sleeve.

8. A smoke consuming device comprising, in combination, a flue adapted to have one wall in contact with the fire, and an opening to admit gases from above the fire, an air pipe to admit air to said flue, means to admit steam with said air comprising an enclosed receptacle located within the heater, a pipe connecting the top of the receptacle with the interior of said air pipe, a reservoir located outside the heater, a pipe connecting said reservoir and the bottom of said receptacle, the top of the reservoir being below

that of the receptacle, and a check valve in the last named pipe.

9. A smoke consuming device comprising, in combination, an annular fire pot comprising spaced inner and outer walls, and annular closures for the top and bottom of the space between said walls to provide an annular flue, a smoke pipe connected to said flue, said top closure having an opening adjacent said smoke pipe to admit gases from above the fire to said flue, a partition between the smoke pipe connection and opening, a collar surrounding and spaced from said smoke pipe, having its lower edge in contact with said top closure about said smoke pipe connection and said opening, whereby said gases will be drawn downward to said opening from above the fire pot.

ROY G. MAKINSON.
